UNITED STATES PATENT OFFICE.

ANNA S. FRIDOLPH, OF KANSAS CITY, MISSOURI.

SPRING CLASP.

Application filed August 29, 1921. Serial No. 496,459.

To all whom it may concern:

Be it known that I, ANNA S. FRIDOLPH, a citizen of the United States, residing at Kansas City, in the county of Jackson and State of Missouri, have invented a certain new and useful Improvement in Spring Clasps, of which the following is a complete specification.

This invention relates to spring clasps and more especially to clasps of that class exemplified by Patents Nos. 1,089,829 and 1,186,656, issued to me on March 10, 1914 and June 13, 1916, respectively, my particular object being to produce a more durable and efficient and at the same time simpler and more attractive clasp than those referred to, which can be adapted to fastening scarfs, ribbons, laces and the like, as well as for retaining the hair in place in a neat and attractive manner.

A further object is to produce an ornamental clasp comprising a body portion having tapered roll edges and a pin pivotally interlocked at one end to the body and adapted when closed against the said body, to be automatically secured in such position by such roll edges, with locks of hair or the ends of scarfs, lace collars and the like, clamped firmly together.

With these objects in view the invention consists in certain novel and useful features of construction and combinations of parts as hereinafter described and claimed; and in order that it may be fully understood reference is to be had to the accompanying drawing, in which:

Figure 1 is a face view of a spring clasp embodying the invention.

Figure 2 is a central longitudinal section of the same with the pin element in open position.

Figure 3 is a face view with the pin in the same position as in Figure 2.

Figure 4 is an enlarged cross section on the line IV—IV of Figure 1.

Figure 5 is a cross section on the line V—V of Figure 1.

Figure 6 is a face view of a clasp with a single bar pin as distinguished from the double bar pin of the preceding figure.

Figure 7 is a perspective view of a multiple pin of the type shown by Figure 6.

Figure 8 is a section on the line VIII—VIII of Figure 7.

Referring now to the drawing in detail,

where like reference characters identify corresponding parts, a blank of suitable material of imperforate or filigree construction, comprises a central or body portion 1 and side wings which are bent spirally to produce parallel side roll edges 2, the blank being of such contour that when such roll edges are formed they terminate in tapered ends 3 forming flaring mouths 4, the mouths communicating with longitudinal spaces between the body portion and the inner ends of the rolls, as indicated at 4^a.

At one end the body is projected substantially beyond the adjacent tapered ends 3, and is formed with a pivot loop or eye 5 for receiving pivotally one end of a double bar or U-shaped pin 6, the sides of the pin normally standing in line with the inner sides of the rolls so that when the pin is swung to closed position its sides will engage the tapered inner sides or walls of the adjacent flaring mouth and be compressed inwardly until said sides enter the spaces 4^a, when they will spring outwardly to normal position, thus retaining their position under the inner sides of said rolls, and likewise retain firmly in position locks of hair or the ends of scarfs, ribbons or the like. The pin is slightly longer than the body portion so as to project beyond the same at its free end so that the operator, by applying pressure or a pull on the projecting or free end of the pin, can open the same, it being noted that as the pull is applied the sides of the pin near the free end thereof engage the walls of the adjacent flaring mouth and are compressed inwardly thereby in the same manner that the sides near their pivoted ends were compressed by the adjacent ends of the roll edges when closing the pin. When the pin is in closed position it occupies substantially the position with respect to the roll edges as indicated by Figures 4 and 5.

In the construction shown by Figures 6 and 7, the principle of construction and mode of operation is the same. In this case, however, the projecting end of the body portion numbered 7 in this instance, is formed with an opening, and the pin is of single bar type as at 8, and is formed at one end with a loop 9 extending pivotally through the opening in the extension 7, it being noted also that in this case the single bar pin is of diameter slightly exceeding the space between the roll edges 2, and that the

entire resiliency or yielding action must be on the part of the said roll edges, whereas in the construction shown by Figures 1 to 5 inclusive, the sides of the pin may yield as well as making provision for a slight yielding by the roll edges 2. The operation of closing and opening in the construction shown by Figure 6, is similar to that in Figures 1 to 5 inclusive. In Figure 7, a multi-
ple-type pin is shown, the same comprising a series of the bar pins connected near the pivoted ends by a bridge or tie 10. This type of pin, which in other respects is similar to that shown by Figures 6 and 8, is designed primarily as a hair waving pin, though it may be put to other uses.

From the above description it will be apparent that I have produced a spring clasp embodying the features of advantage set forth as desirable, and which may be modified in minor particulars without departing from the principle of construction or mode of operation involved.

I claim:

1. A spring clasp comprising a body-portion having parallel roll edges extending for substantially the full length of and overlapping and spaced from the body-portion, and a pin pivoted at one end to the body-portion; the pin and roll edges bearing a laterally-yielding and wedge relation at their opposite ends to insure engagement and disengagement respectively, when the pin is operated pivotally under sufficient power to close or open it.

2. In a spring clasp, a member having a body-portion and side roll edges; said edges being spaced at their inner sides from the body-portion and having tapered ends to provide an interposed longitudinal slot having flaring mouths at its ends, and a pin pivoted at one end to said clasp and adapted for engagement with the roll edges thereof.

In witness whereof I hereunto affix my signature.

ANNA S. FRIDOLPH.
